FOREIGN PATENT DOCUMENTSEM RGN * 8/2017
004131340-0001*Primary Examiner* — Kevin K Rudzinski*Assistant Examiner* — Richard Kearney(57) **CLAIM**

The ornamental design for a zipper, as shown and described.

DESCRIPTION

FIG. 1 is a perspective view of a zipper showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross sectional view thereof, taking along line 8-8 of FIG. 2;

FIG. 9 is a perspective view thereof, showing the zipper in a condition of use;

FIG. 10 is a perspective view thereof, showing the zipper in an alternate condition of use; and,

FIG. 11 is an exploded view of the zipper.

The dash-dot-dash broken lines illustrate the bounds of the claims. All broken lines form no part of the claimed design.

1 Claim, 10 Drawing Sheets(56)
